(57) **CLAIM**

The ornamental design for a disc jockey controller for a tablet computer, as shown and described.

DESCRIPTION

FIG. 1 is a top, front, and right side perspective view of an embodiment of a disc jockey controller for a tablet computer showing our new design;

FIG. 2 is a front elevation view thereof;

FIG. 3 is a rear elevation view thereof;

FIG. 4 is a top view thereof;

FIG. 5 is a bottom view thereof;

FIG. 6 is a left side elevation view thereof; and,

FIG. 7 is a right side elevation view thereof.

The tablet computer in the dock, bottom and rear panels, and screws and connectors depicted in broken lines are for environmental purposes only and form no part of the claimed design.

1 Claim, 6 Drawing Sheets
